UNITED STATES PATENT OFFICE

CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK

TRAIN CONTROL

Application filed October 21, 1922. Serial No. 596,101.

This invention relates to automatic train control systems for railways, and more particularly to a system in which certain speed restrictions are enforced.

According to this invention, it is believed desirable to make the automatic train control system supplement the block signal system and the vigilance and care with which engineers observe and obey the signal indications with rare exceptions, in order that all of the safety of train movement now attained without train control may be retained, and the automatic train control system reserved to safeguard the train in those exceptional cases where the engineer fails for some reason to perform his duties properly. If the vigilance of the engineer is in some manner maintained, it will be evident that, before an accident can result, not only must the signal system and the engineer fail, but also the train control equipment; whereas if the engineer becomes lax in his observance of the indications of the block signals or careless in acting upon these indications, the safety of the train is largely dependent upon the proper performance of the automatic train control system. As soon as an automatic system is applied to a locomotive, designed to perform some of the duties of the engineer, he will naturally be inclined, unless in some way restrained, to rely upon this system; and to maintain vigilance in the manner indicated, it becomes necessary to encourage or force the engineer in some way to perform his duties in the usual way in spite of the train control equipment.

In accordance with the theory of maintaining vigilance, above outlined, it is contemplated in this invention to provide a device, conveniently termed an acknowledging device, which the engineer must operate prior to passing each restrictive signal or corresponding control point, under penalty of being required to stop, get down, and reset the apparatus, or in some other way be subjected to trouble or discipline. In other words, at each restrictive signal or corresponding control point, the brakes are automatically applied unless the engineer antic-

ipates such application by taking an appropriate action.

In addition to this acknowledging device, this invention contemplates the provision of automatic mechanism compelling the train upon entering a caution block, or also a danger block, if desired, to reduce its speed to some predetermined minimum or control speed, such as 20 miles per hour. It is contemplated that this enforced reduction in speed serves to prevent the engineer, carelessly or intentionally, running his train through a caution block, after having properly acknowledged the restrictive signal, without reducing speed, perhaps in hopes that the next signal ahead will change to a more favorable indication by the time the train reaches it. Putting it another way, the purpose of compelling reduction in speed in each caution block, assuming proper acknowledgment of the signal has been made, is to obviate the objectionable practice followed by some engineers in "running the caution signal," that is, running their train through a caution block without full regard to their speed and braking distance, under the conviction that the signal in advance will have cleared up by the time it is reached.

Generally speaking, the primary objects of the present invention are to devise a simple and efficient combination or organization of parts and circuits by which the engineer is compelled to acknowledge each restrictive signal indication, and is also required to reduce his speed to some selected control speed. Other specific objects, characteristic features, and advantages of the invention will appear hereinafter as the description progresses.

In describing the invention in detail, reference will be made to the accompanying drawings, in which:—

Figure 1 illustrates in a simplified and diagrammatic manner one form of car apparatus and trackway equipment embodying the invention, the various parts and circuits being shown more with the purpose of facilitating explanation and understanding of the invention than with the object of showing the precise construction and arrangement preferably employed in practice;

Fig. 2 is a diagrammatic view, similar to Fig. 1 illustrating a slightly modified arrangement of car equipment; and

Fig. 3 is a fragmentary diagrammatic view showing a still further modified construction of the car apparatus.

Referring first to the embodiment of the invention shown in Fig. 1, and taking up the trackway equipment, the track rails 1 are bonded together in the usual way by bond wires and channel pins, or the like; and these track rails are divided into blocks of the desired length by insulated joints 2 in conformity with recognized block signal practice, only one block E with the portions of adjacent blocks D and F being shown. Since the devices and circuits associated with these blocks are the same, for convenience they will be given the same reference characters with distinctive exponents. Each block is equipped with a normally closed track circuit of the usual and well-known construction, comprising a track battery 3 and a track relay 4, with the usual adjuncts, such as limiting resistance, battery chutes, relay boxes, and the like, all as commonly used in practice.

It is contemplated that the train control system will be used as a supplement or an adjunct to some suitable type of automatic or auto-manual block signal system, including fixed track signals of the semaphore, color light, or other type. The various forms of the signals, control circuits, and relays suitable for this purpose are now well-recognized in the art; and to avoid useless complication, semaphore signals 5 at the entrance to each block have been shown conventionally, without any attempt to illustrate their well-known structure and control circuits, it being understood that these signals will give the usual clear, caution, and stop indications, dependent upon the presence or absence of trains in the corresponding block and in the next block in advance. The adaptability of the train control system of this invention to block signal systems of other types, employing other types of trackway signals or other forms of control circuits, is considered to be so evident as to require no specific illustration or description.

The train control system of this invention in its simplest form, which has been selected for the purpose of explaining the nature of the invention, requires the communication of a stopping impulse or influence from the trackway to each passing vehicle at each caution signal, with or without a similar stopping impulse at each stop or danger signal; and for this purpose there is located adjacent to the entrance end of each block (traffic being from left to right as indicated by the arrow) a track element or inductor T, which may be disposed a short distance in the rear of the insulated joints 2 defining the entrance to the block in question, or opposite such

joints, or a distance in advance thereof, depending upon the type of control circuits for these track elements. In the particular arrangement of control circuits shown, track element T is located a short distance in the rear of the insulated joints at the entrance of the corresponding block, and the controlling condition of said track element is governed by a line relay 6 that is controlled by the track relays of the corresponding block and the next block in advance, as clearly shown on the drawing. It is noted here that the various circuits are shown in a conventional manner with the reference character B indicating a connection directly to one terminal of a battery or other source of current and the reference characters C or N indicating a direct connection to the other terminal of the same source, it being understood that several batteries or other sources of the appropriate voltage and current capacity may be used in the respective circuits in conformity with engineering practice.

The track element or inductor T comprises in general a U-shaped core or yoke 7 of soft iron laminations, a coil or winding 8 on said core, together with a suitable support or mounting for housing and protecting said core and coil which may take various forms and which for simplicity is not shown. The yoke 7 is provided with enlarged pole pieces which are disposed a considerable distance above the top of the track rails and outside one of the rails. In one specific arrangement, the track inductors are located with their pole pieces about 2½" above the level of the top of the running rails and with their center lines about 19" outside of one or the other of the running rails. The coil 8 of the track inductor T is connected through a front contact 9 of corresponding line relay 6, and thus is in a closed circuit of preferably low resistance when said line relay is energized.

The locomotive, motor car, or other railway vehicle, equipped with this invention is shown diagrammatically as comprising two pairs of wheels and axles 10 and 11. Carried on this vehicle is a car element or receiver L, which is housed and protected, and suitably supported from the frame or other part of the vehicle in position to pass directly over the track inductors T. The car element L comprises a U-shaped core or yoke 12 of soft iron laminations, said cores being similar in size to the cores of the track inductors and having similar enlarged pole pieces. On one leg of the core 12, preferably the forward or leading leg, is a primary or exciting coil P; and on the other leg is a secondary or receiving coil S. It is noted here that only one car element L has been shown, permitting the locomotive or other vehicle to travel pilot first in the normal direction of traffic and receive influences from the track inductors T; and it is

to be understood that if it is desired to exert control with the locomotive traveling tender first in the normal direction of traffic, an additional car element and suitable control means is to be employed. This and other adjuncts or adaptations of the specific construction forms no part of this particular invention, and to avoid undue complication in illustration and description, these auxiliary features are not shown.

A track inductor T in the active stopping condition produces an influence upon the car element L, specifically a change of current in the secondary coil S thereof, as explained more fully hereinafter; and a suitable electro-responsive device, responsive to such current changes in said secondary coil, is provided to translate or convert this inductive influence or impulse into control for the working parts of the car equipment. While this electro-responsive means, or translating equipment may take various forms, there is shown an arrangement comprising a main control relay CR, and a repeater relay RR. These relays are, of course, constructed and have electric characteristics suitable for their respective duties, and also are properly supported upon the locomotive or other vehicle so as to be immune to shocks, jars, and vibration. The armature of the control relay CR is shown conventionally and is pivotally supported at the middle and rocked about its pivotal axis by a spring, and in the other direction by magnetic attraction if the coils of the relay are sufficiently energized. This armature or contact finger 13 cooperates with two stationary and insulated contacts, shown conventionally as arrows, which are normally closed while said relay is effectively energized. The repeater relay RR is provided with a similar armature or contact finger 14 pivoted at its center and provided with two front contacts and a back contact as shown.

The control impulses or influence communicated from the trackway to the vehicle in accordance with this invention, is utilized in a suitable manner for the regulation of the movement of said vehicle, preferably by operating a suitable brake applying mechanism. It is contemplated that such brake applying mechanism will act directly upon the air-brake system commonly used, and in some one of the well-known ways, produce an automatic brake application in the proper manner, suitable provisions being made in this mechanism to prevent the engineer recharging and releasing, to produce a limited reduction in brake pipe pressure, and otherwise act upon the air-brake equipment in accordance with recognized and accepted practice. The particular character of this brake applying mechanism, however, forms no part of the present invention, and consequently such mechanism or the primary control therefor, has been illustrated conventionally and desig-

nated K. This brake setting device K is one which, if deenergized, acts to produce an automatic brake application, and which, if energized, permits the release of the brakes. This device K operates contacts shown conventionally as an insulated disk 15 and arrows co-operating therewith, the circuit through said contacts being normally closed while said device is energized and inactive, and being automatically opened when said device is deenergized to apply the brakes.

In conformity with the principle of enforcing vigilance on the part of the engineer, as previously explained, a hold-by or acknowledging device or contactor, designated as a whole A, is provided as a part of the car equipment shown in Fig. 1. This acknowledging contactor A is shown in a simplified form and comprises a plunger 16, with a suitable knob for facilitating its manual manipulation, which is supported in guides 17, and is pressed upward by a spring 18 between its knob and one of its guides. This plunger 16, when depressed manually in opposition to the spring 18, forces a spring 19 contact finger 19 into engagement with a stationary insulated contact, shown conventionally as an arrow. At the same time another rigid contact finger 20 is released and is moved downward by a tension spring 21 at a rate determined by a suitable dash-pot or timing mechanism 22. This rigid contact finger 20 is provided with a resilient spring 23 and stop which cooperates with a stationary contact (shown as an arrow) in such a way that when said finger 20 attains a predetermined lower position, the spring 23 engages the stop and is pulled out of contact with its stationary contact.

From the foregoing explanation of the diagrammatic showing of the acknowledging contactor A, it will be observed that this device generally speaking, comprises normally open contacts, which are closed when said contactor is manually actuated, and normally closed contacts 23, which are automatically opened if the contactor is held in its actuated position longer than a predetermined time. In connection with this acknowledging contactor A there is preferably employed a suitable signal operable upon the flow of current, this signal being shown conventionally as a bell 24, which is of the single stroke type or one which does not cause intermittent interruption of its circuit while operating.

The engineer is penalized for his failure to take appropriate action when required by being compelled to operate the reset device, which is preferably located so that it is accessible only from the ground and can not be manipulated until the train has been brought to a stop, or this device is sealed or arranged in some other suitable manner, so that its operation involves considerable annoyance, publicity, subsequent displacement or similar

penalty. It may be said that the purpose is to make the operation of the reset device, as compared with the simple manipulation of the acknowledging contactor A, so objectionable that the engineer will prefer to work the acknowledging contactor rather than be obliged to operate the reset device. This reset device, as shown in the simplified form of the invention, comprises a spring push button or switch blade 25, controlling a normally opened contact and a normally closed contact.

In order to enforce or compel a reduction in speed to a predetermined minimum or control speed, as previously explained, the car equipment shown in Fig. 1, comprises speed control apparatus of the cyclic type employing a permissive speed cam and a speed-responsive device determining the existing actual speed. The speed-responsive device or governor G is connected to and driven by a shaft 26, supported in suitable bearings 27 and suitably coupled to one of the axles of the vehicle, as by bevel gears 28. The shaft 26 is rotated at a speed proportional to that of the vehicle, and the weights 29 of the speed-responsive devices are thrown outward by centrifugal force against the opposition of a spring 30 to lower a sliding sleeve or collar 31 to a position corresponding with the instantaneous existant speed of the vehicle. Thus the position of the collar 31 corresponds to the actual speed of the vehicle. This collar 31 is provided with an insulated disk 32 arranged to engage one of a pair of spring contacts 33 and cause separation thereof for speeds in excess of a predetermined maximum, this maximum speed corresponding to that at which a train may safely run normally under clear signals, say, 60 miles per hour. The collar 31 also shifts up and down the outer end of an arm 34 fixed to a rocking shaft 35, the connection between the arm 34 and said collar 31 being made in a well-known manner and so as not to interfere with rotation of said collar. The rocking shaft 35 has arms 36-36¹ which are pivotally connected to one end of corresponding floating levers 37 and 37¹. Thus, one end of the floating levers 37-37¹ are automatically shifted to different positions corresponding to the existing actual speed of the vehicle.

The shaft 26 is coupled by bevel gears 38, with a shaft 39 having a universal connection to an auxiliary shaft 40. Fixed to the auxiliary shaft 40 is a worm 41 arranged to drop into mesh with a worm gear 42 on a cam shaft 43, said cam shaft being supported in suitable bearings 44. The worm gear 42 has a cut-away portion in its periphery as shown. The auxiliary shaft 40 tends to drop by its own weight to bring the worm 41 into mesh with the worm gear 42 and is held in its raised position by a cam starter magnet or solenoid CS, the core or armature 45 of which

has a pivotal connection to a sliding sleeve 46 loosely mounted on said shaft 40. The upward and downward movement of the shaft 40, throwing the worm 41 out of and into engagement with the worm gear 42, is used to open and close certain contacts; and in the simplified arrangement shown, a reciprocable bar 47, having sliding and rotary connection with the shaft 40, and supported by fixed guides 48, shifts spring fingers 49, 50 and 51 by insulated pins. With the shaft 40 raised as shown, the spring fingers 50 and 51 are forced into engagement with cooperating contacts shown conventionally as arrows, while the finger 49, is forced out of engagement with its cooperating contact. When the shaft 40 drops, fingers 50 and 51 are shifted to break contact, and finger 49 is shifted to make contact.

The cam shaft 43 has fixed thereto two permissive speed cams 52 and 53, one 52 for controlling the brakes, and the other 53 for controlling a suitable preliminary warning signal. These cams 52, while shown in a simple form, are in practice carefully shaped with due regard to the travel of the collar 31 of the speed-responsive device G and the relative movements of the other parts of the apparatus, so as to prescribe a variable limiting or permissive speed for the train at all points in its travel, as said cams are turned, corresponding to a predetermined speed-distance curve. These permissive speed-distance curves are in practice based upon the braking performance of the train in question; and generally speaking, these curves will show the different speeds at the different points in the block at which the train may be traveling and yet be brought to a stop by an automatic brake application before reaching the end of the block. The precise shape of these permissive speed curves, however, is subject to considerable variation according to the requirements of the railroads, and curves may be based upon braking performance on the level grade or a down grade or a given weight of train. Irrespective of the detail factors determining the shape of the cam, it will be readily understood that this cam is intended to set up a gradually reducing speed limit as the train progresses after the cam movement is started, so that the train is compelled to maintain its speed below a gradually reducing limit, otherwise an automatic brake application occurs. The cams 52 and 53 although preferably based upon the same factors, are slightly different in shape, so that a warning signal controlled by cam 53 will be given a short interval of time before the brakes are automatically applied by the action of the other cam 52, thereby providing a preliminary warning signal to advise the engineer that his speed is approaching the limit at which a brake application will occur.

The floating levers 37-37¹ carry at their ends freely revoluble rollers 54 and 54¹ which bear upon the edges of the respective cams 52 and 53. Contact operating members 55-55¹ are pivotally connected at intermediate points of the floating levers 37-37¹; and when these intermediate points have been raised to a predetermined extent, insulated striking pieces on said members 55-55¹ engage contact springs of a pair of contacts 56-56¹, respectively, thereby interrupting circuits therethrough. Springs 57 and 57¹, connected to the contact operating members 37-37¹, serve to maintain the rollers 54-54¹ in contact with the cams.

The cams 52 and 53 are shown in their maximum speed positions, and it will be noted that the radii of these cams increase as they are turned in either direction from the normal or initial position shown. This increase in radius forces up the rollers 54-54¹ raising the corresponding ends of the floating levers 37-37¹; and it will be evident that unless the other ends of said floating levers are sufficiently low, that is, the actual speed is sufficiently low, the contacts 56 and 56¹ will be opened. It may be added that this particular construction shown and permitting control of circuits, dependent upon the position of a part changeable in accordance with the actual speed and another part changeable in accordance with the desired permissive speed, is diagrammatic and simplified in its character and is intended to exemplify a function or principle.

The cam shaft 43 is biased or urged to the normal or initial position shown by a spring 58 anchored at one end to a stationary part, and coupled at the other end to a crank arm 59 fixed on said shaft. On the cam shaft 43 is fastened an arm 60 which is arranged to engage one or the other of two contact springs 61, 61¹, depending upon the direction of rotation of the cam shaft, after said cam shaft has attained its minimum speed position; and when the spring 61 or 61¹ is thus engaged by the arm 60, it is shifted into contact with a suitable fixed contact, shown conventionally as an arrow. If the closure of circuits in this way fails to cause restoration of the cam shaft by the action of the spring 58 to its normal or initial position, as hereinafter described, the cam shaft will be rotated a short distance further until the worm 41 engages the cut-away or mutilated portion in the worm gear 42, whereupon further movement of the cam shaft ceases.

The maximum speed prescribed by the cam 52 in its normal or initial condition is preferably the same or slightly higher than the speed at which the contacts 33 are opened directly by the movement of the collar 31 of the speed-responsive device G. The radius of the warning signal cam 53 when in its normal

condition, is selected so as to cause operation of contacts 56¹ and the giving of the warning signal at a speed somewhat less than the maximum speed at which the contacts 33 open, say at 55 miles per hour if contacts 33 open at 60 miles per hour, so that the engineer is given an advance warning that his speed is approaching the maximum normal running speed permitted. The minimum speed position of the cam shaft, that is, the position at which the arm 60 closes contacts 61 or 61¹, preferably corresponds to some moderate control speed, such as 20 or 25 miles per hour, this minimum or control speed being such that the engineer may release the brakes and proceed after coming down to such speed without having to stop. In this connection it is obvious that the speed limits above mentioned should be different for freight trains than for passenger trains, because freight trains have different normal running speeds and also can not release the brakes without stopping at as low a speed as a passenger train.

The warning signal above mentioned is shown diagrammatically as a whistle W, operated by compressed air or the like whenever its controlling solenoid is deenergized. The circuit for normally energizing the control magnet of this whistle W merely includes a suitable source of energy as a battery and the contact 56¹ and may be readily traced on the drawings.

Operation.—In describing the operation in its various steps, it is expedient to consider first the normal condition or position of the various parts of the car apparatus, including the various circuits controlling these parts, and then take up the action of these parts under different conditions. Parts and circuits of the car apparatus shown in Fig. 1, are in the normal position corresponding to the movement of the train under clear signals.

The main control relay CR is normally maintained energized by a circuit which may be traced as follows:—commencing at B, contact finger 13, front contact, wires 62 and 63, relay CR, wires 64 and 65, contact 51, wires 66 and 67, secondary coil S, to C, it being remembered that the letters B and C indicate connections to the opposite terminals of a suitable battery or other source of energy.

The repeater relay RR is maintained energized so long as the control relay CR is energized by a circuit through a front contact of said control relay and wire 68, as readily traced on the drawings.

The cam starter magnet CS is normally maintained energized by a circuit traced as follows:—commencing at B, wire 69, front contact and contact finger 14 of repeater relay RR, wires 70 and 71, contact 50, wires 72 and 73 and cam starter magnet CS to C.

The train control device K is normally maintained energized by a circuit traced as

follows:—commencing at B, wire 69, front contact of relay RR, wire 74, reset switch 25, wire 75, maximum speed contact 33, wire 76, finger 20 of acknowledging contactor A and its spring 23, wire 77, device K, wire 78, and primary coil P to C.

From the circuit just traced it will be noted that the train control device K is connected in series with the primary coil P, so that if the energizing circuit for said primary coil should become interrupted, or the current flow decreases below a safe value, the train control device K will cease to be effectively energized and will operate to apply the brakes and stop the train on the side of safety.

With the parts in the normal position shown, there is established a continuing maximum speed limit which the train can not exceed without an automatic brake application.

If the train exceeds this maximum speed limit, contacts 33 are opened, breaking the energizing circuit of the device K and applying the brakes. The contacts 56 associated with the cam 52 may be opened at the same

time, assuming that the speed limit for the initial position of the cam 52 corresponds to the speed limit at which contacts 33 open, but the opening of contacts 56 at this time produces no effect since these contacts are shunted

by wires 65, 66 and contact 51. The contacts 56 associated with the warning signal cam 53, however, will open before contacts 33 open and apply the brakes, so that the engineer has an advance warning of a brake application due to excessive normal running speed.

In case the normal running maximum speed limit is exceeded, as soon as the speed has been reduced below this limit by the automatic brake application, or by a manual

brake application, as the case may be, the contacts 33 operated by the speed-responsive device G directly reclose, thereby reenergizing the device K and permitting the brakes to be released and the train to proceed.

In other words, there is no particular penalty imposed for exceeding the maximum normal running speed, that is, the train may proceed at once after the automatic slowing down thereof without being required to stop.

For the first condition to be considered, assume that the train passes a caution signal, that the engineer has been vigilant and has observed this caution signal, and that in recognition of this caution signal he has operated his acknowledging contactor A.

The track inductor T at the caution signal will have its coil 8 open-circuited, so that the core 7 of said track inductor presents in effect a magnetic loop or partial circuit for the core 12 of the car element.

The primary coil P of the car element is constantly energized, as above explained, and tends to send flux through the core 12; and as this core passes over the core 7, the reluctance of the magnetic circuit through the primary and secondary

coils P and S is first decreased from normal to a minimum and then increased from a minimum back to normal. By reason of such change in the reluctance, perhaps aided by diversion of flux from leakage paths around the primary coil P, there is a quick change of flux through the secondary coil S, first an increase and then a decrease. This quick change of flux induces a voltage in the secondary coil S which produces a single cycle of alternating current; and either the first or the second wave of this induced cycle of voltage, depending upon the connections, opposes the battery or other source supplying energy to the main control relay CR, thereby reducing the current in the coils of this relay to the point where its armature is retracted by the spring. The connections are preferably made so that the relay operates in response to the first half cycle of induced voltage.

Thus, as the train passes an active track inductor T, the relay CR is momentarily de-energized, and being a stick relay holds its contacts open until otherwise energized, and since the repeater relay RR is controlled directly by relay CR, the repeater relay RR likewise opens its front contacts and closes its back contact.

The opening of the front contact of the repeater relay RR deenergizes the cam starter magnet CS, allowing shaft 40 to drop and bring worm 41 into mesh with worm gear 42, thereby commencing the gradual rotation of the cam shaft. At the same time contacts 50 are opened, so that reclosure of the front contacts of repeater relay RR does not cause energization of the cam starter magnet CS, which must be restored by another circuit, as hereinafter explained. In short, the cam is started into operation upon passage over the active track inductor T, and irrespective of the condition of the relays CR and RR, continues in force until restored.

Assume now that the engineer was alert and observed the caution indication of the signal prior to the passage of the vehicle by the active track element, and that the engineer, before deenergization of the relays CR and RR, pressed down the plunger 16 of the acknowledging contactor A. Under these conditions, while the opening of the front contact of relay RR breaks the normal energizing circuit for the device K previously traced, the closure of the open contacts 19 of the acknowledging contactor A establishes a circuit for holding the device K energized in spite of the dropping of relay RR. This auxiliary holding circuit for the device K may be traced as follows:—commencing at battery B, wire 80, contacts 15 of device K, wire 81, contacts 19 of acknowledging contactor A, wire 82, bell 24, wire 83, reset switch 25, wire 75, contacts 33, wire 76, normally closed contacts of acknowledging con-

tactor, wire 77, wire 78, primary coil P to C.

Also, closure of the contacts 19 of the acknowledging contactor A permits re-energization of the main control relay CR, provided the shaft 40 has dropped to start the cam as intended. This pick-up circuit for the relay CR may be traced as follows:— commencing at B, wire 80, contact 15 of device K, wire 81, contacts 19 now closed, wire 82, bell 24, wire 83, wire 74, back contact of relay RR, wire 84, contact 49 now closing by dropping of shaft 40, wires 85 and 63, relay CR, wire 64, contacts 56, wire 67, secondary coil S to C.

15 As soon as relay CR is reenergized to close its front contacts, relay RR is likewise reenergized, thereby establishing the normally closed energizing circuit for the device K, so that the contacts 19 may now be opened

20 without the application of the brakes.

From the foregoing it will be noted that the engineer, by making timely operation of the acknowledging contactor accomplishes two things, first, avoids the deenergization of the device K and the resultant brake application that would otherwise occur upon dropping of the relays CR and RR, and second, restores the relays CR and RR. It will also be noted that these functions can only be

25 performed so long as the contacts 15 of the device K are closed, that is, before the device K has operated. Consequently, the operation of the acknowledging contactor A must be made prior to the passage over the active

30 track element, and can not be made later. In short, the engineer, must watch out for the signals, and can not wait until, by the application of the brakes or otherwise, he is advised that a caution control has been received.

35 The bell 24 is sounded when the front contacts 14 of the relay RR open, that is, providing the contacts 19 have been closed by the

40 engineer, said bell being shunted by wire 74 and the front contacts 14 of relay RR so long as contacts 19 are closed, and does not sound until said front contacts 14 open. In other words, after the contacts 19 have been closed by manual operation of the acknowledging contactor A, a supplemental partial circuit,

45 including the bell 24, is established in multiple with the front contact 14 of the relay RR and wire 74, this partial circuit starting at B, wire 80, front contacts 15 of the device K, wire 81, contacts 19 of the acknowledging

50 contactor A, wire 82, bell 24 and wire 83.

By reason of the much greater resistance of the bell 24, as compared with the very low resistance of the wire 74 and the front contact 14 of the relay RR, practically no cur-

55 rent flows through the bell 24 under these conditions; but as soon as the front contact 14 of the relay RR opens, the bell 24 is connected in series with the device K and the primary coil P and is supplied with

60 enough current to cause it to sound. The

bell 24 serves to inform the engineer that he has passed the track inductor and may shortly release the acknowledging contactor. The sounding of this bell 24 also informs the engineer that the system is working properly.

70 In order to prevent the engineer from defeating the purposes of the system by fastening down the acknowledging contactor A, the time control contacts 23 are provided, so that, if the plunger 16 is held down too long, the energizing circuit for the device K is directly opened and the brakes applied. The adjustment of the dash-pot or timing device 22 is such that the time for opening of the contacts is long enough to give the engineer reasonable latitude in passing an active inductor, but too short to permit him to pass two signals in succession by the same manipulation.

75 Assume now that the engineer is asleep, incapacitated, or for some other reason fails to observe or correctly interpret the caution signal indication and consequently does not make a timely operation of the acknowledging contactor. Under these conditions, when the relays CR and RR assume the de-energized position, the normally closed energizing circuit for the device K is broken and there being no auxiliary maintaining circuit,

80 said device at once operates and applies the brakes. Upon such operation the contacts 15 open thereby preventing restoration of the relay CR by manipulation of the acknowledging contactor A. Incidentally, the cam starter magnet is deenergized and the cam is started in operation in the same manner as if the engineer had properly acknowledged the signal; but the brakes are applied and the train is immediately brought to a stop. Before

85 the device K can be reenergized and the brakes released, the reset switch 25 must be actuated; and since the operation of this switch is attended with a penalty, as previously explained, it is clear that the engineer

90 would much prefer to watch out for the signals and operate his acknowledging contactor. Operation of the reset switch 25 supplies current from the battery to the wire 74 and through the back contact of relay R picks up

95 relay CR, and consequently relay RR. When the reset switch is released and allowed to return to the normal position shown, then the train control device is reenergized and the train may proceed, subject, however, to

100 the speed limits that may be enforced by the cam. It will be observed that the engineer can not fasten down the reset switch 25, because the train control device can not be energized and the train proceed until the switch is restored to the normal position.

105 In both of the cases above discussed, whether the engineer properly acknowledges the signal or not, the cam shaft and cams 52 and 53 are geared to the wheels, thereby imposing gradually reducing speed limits. If

the engineer does not himself regulate the speed of his train properly, guided by the warning signal, and allows the speed at any time to exceed the permissive speed, contacts 56 open and break the energizing circuit for the relay CR, which in turn deenergizes relay RR and applies the brakes. The engineer must then stop the train and operate the reset switch 25.

- 10 If the acknowledging contactor is operated at the time contacts 56 open, the device K may be maintained energized, as previously explained, but the relay CR can not be picked up since its circuit is broken at contacts 56; 15 and unless the speed is quickly reduced to reclose contacts 56, the contacts 23 of the contactor A will open and apply the brakes.

If, however, the engineer properly controls the speed of his train, the cam shaft is turned 20 after a predetermined distance in travel to the point where the arm 60 thereon closes contacts 61 or 61¹, whereupon the cam starter magnet CS is reenergized by a circuit as follows, it being remembered that relays CR 25 and RR must be picked up at this time:— battery, wire 69, front contacts of relay RR, wire 70, wire 86, contact 61 or 61¹, wires 87 and 78, cam starter magnet CS to C. As soon as the cam starter magnet CS is energized, it lifts the shaft 40, closing contact 50, so that said magnet is maintained energized by its stick circuit, independently of contacts 61 or 61¹. As soon as worm 41 is thrown out of mesh with worm gear 42, the 35 cam shaft is restored to its normal or initial position by the spring 58. The train may now run at any speed below the maximum prescribed by contacts 33 until the cam is started into operation again.

- 40 Fig. 2 illustrates a slight modification of the invention, employing the same apparatus and devices shown in Fig. 1, but using a different form of control for starting the cam shaft. Since most of the devices and circuits 45 are the same and have the same functions as those already described in connection with Fig. 1, these parts and electrical connections have been given the same reference characters, allowing the description of Fig. 1 to be 50 used also for Fig. 2 in most respects.

In the modified arrangement of Fig. 2, the cam starter magnet CS is controlled by the acknowledging device A, and by the contacts 15 of the brake setting device, so that whenever 55 said acknowledging contactor is actuated, or the brake setting device K is set into operation, the cam starter magnet CS is deenergized. The cam starter magnet CS has a stick circuit through contacts 50, and picking up circuit through contacts 61-61¹. Another difference is that contact 51 shown in Fig. 1, instead of being opened when the shaft 40 drops, is opened when the cam shaft 43 has slightly turned from its initial position. Another 65 difference is that the contact 49 includ-

ed in the pickup circuit for the relay CR is omitted, and said relay is picked up at once when the acknowledging contactor is actuated, whether the cam starter is deenergized or not.

The operation of the modification of Fig. 2 is substantially the same as that of Fig. 1 and need not be described in detail. The engineer must actuate the acknowledging contactor A at each active track inductor in order to avoid deenergization of the brake setting device K. If the control relay CR in releasing once causes deenergization of the brake setting device K and opening of its contacts 15, the brakes are held applied until the parts are reset by manipulation of reset switch 25. Unless, therefore, the engineer acknowledges at each caution signal or corresponding control point, the brakes are applied and the apparatus must be reset from the ground. Whenever the acknowledging contactor is actuated, the cam starter magnet CS is deenergized and can not be reenergized until the cam has run down to its minimum speed position closing contacts 61 or 61¹.

The important distinction between the disclosures of Figs. 1 and 2, is that the cam is started by the releasing of the relays by the reception of an influence from the trackway in Fig. 1, but is started by the act of acknowledging in the arrangement of Fig. 2. The purpose of arranging it so that every operation of the acknowledging device starts the cam is to make it more sure that the cam will always be started at each caution signal. To illustrate, it may happen that the proper influence may not be received at the entrance to some particular caution block, for some reason or another; but the engineer, not knowing this, will operate his acknowledging contactor in the usual way, so that the cam will be started in operation and the desired speed limits imposed in spite of the fact that the control influence was not received. In other words, the vigilance and care with which engineers almost without exception will, it is believed, observe restrictive signal indications and operate the acknowledging contactors, acts as a check upon the proper performance of the automatic influence communicating equipment, so that there must be a failure on the part of the engineer as well as the failure to receive an influence from the trackway before there can be a failure to start the cam.

Another embodiment of the invention, employing similar principles and functions hereinafter explained, is shown in Fig. 3. In this modified arrangement, generally speaking, the brakes are applied as the train passes each caution signal or corresponding control point, but if the engineer has properly acknowledged the signal, the brakes may be released after the train has reached a predetermined speed. Incidentally, if the train

should happen to be traveling at a speed lower than this predetermined control speed at the time it passes the caution signal, no automatic brake application will occur provided the engineer properly acknowledges the signal.

The modification of Fig. 3 employs many of the devices hereinbefore described and for convenience corresponding parts have been given the same reference characters. The influence communicating means is the same, including the main control relay CR and the repeater relay RR. The acknowledging contactor A is the same, with its normally open contact 19 and its normally closed time controlled contact 23. The reset switch R performs the same function as previously described, but on account of the difference in the circuit arrangement, the normally closed contact of the switch is provided with two separate switch blades or contacts 25 and 25¹. The brake setting or train control device K is the same and is provided with the same normally closed contact 15. The speed-responsive device or governor G has the insulated collar 32 which opens contacts 90 unless the speed of the train is below some moderate control speed, such as 20 miles per hour.

Operation of Fig. 3.—Normally, that is, when the train is traveling under clear traffic conditions, the main control relay is maintained energized by a stick circuit through its front contact and the secondary coil S as will be readily traced on the drawings. The repeater relay RR is maintained energized by a stick circuit:—commencing at B, front contact 13 of relay CR, wires 91 and 92, front contact 93 of relay RR, wires 94 and 95, relay RR, and wire 96 to C. The brake setting or train control device is maintained energized normally by a circuit as follows:—commencing at B, wire 97, front contact 98 of relay RR, wire 99, normally closed contacts 23 of acknowledging contactor A, wire 100, closed contact 25¹ of reset switch R, wire 101, device K, wire 102, through the primary coil to C.

When the train passes an active track inductor, the relay CR is momentarily deenergized as previously explained. Assume for the first condition that the engineer properly acknowledges the signal by actuating the acknowledging contactor A, and that the speed of the train is above the control speed at which contacts 90 open. The releasing of the relay CR breaks the stick circuit for the relay RR, and contacts 90 being open, relay RR remains deenergized. The opening of the front contact 98 of relay RR breaks the energizing circuit for the device K, applying the brakes. In this connection, it should be noted that the speed contacts 90 when closed, form a shunt for the stick contacts 93, so that the relay RR functions as an ordinary non-stick relay when the speed of the train is be-

low the control speed limit but functions as a stick relay when the speed is above this value. This deenergization of the device K, however, is briefly retarded by the fact that when contact finger 98 drops and makes its back contact a deenergized closed circuit including the device K and primary coil P is formed; and in accordance with well-known principles of self induction, and the dissipation of the energy stored in a magnetic field linked with a closed circuit, the current in this circuit dies down gradually. When the engineer depresses the acknowledging contactor A, a pick-up circuit for restoring the relay CR is formed as follows:—commencing at battery B, back contact 103 of relay RR, wire 104, contacts 15 of device K, wire 105, contacts 19 of acknowledging contactor A, wires 106, 107 and 108 to relay CR, and thence through the secondary coil to C. The operation of the device K is delayed in the manner above described long enough to permit relay CR, which is quick-acting, to pick up after dropping of relay RR before contacts 15 open. The relay CR once picked up is held up through its normal stick circuit. After the train has been brought down to the control speed by the action of its brakes and contacts 90 close, relay RR is picked up, since relay CR has been restored, and the contacts 90 establish a shunt for the stick contacts of relay RR, as can be readily seen on the drawings. Consequently, with relay RR again picked up, the device K is energized, and the brakes may be released. Since the relay RR is held up through its stick circuit independently of the opening of contacts 90, a train thereafter may travel at any speed until it receives another impulse from the trackway; but it has been assured that the train has been brought down to the control speed in the caution block and has not maintained an excessive speed.

For the next case, assume that the engineer properly acknowledges the caution signal, and that the speed of the train at that time is below the control speed at which contacts 90 may be open. Under these conditions, the relay CR is restored as before, relay RR is immediately picked up and the device K is only momentarily deenergized if at all.

For the next condition, assume that the engineer is asleep or for some other reason fails to acknowledge the signal. Under these conditions, when relays CR and RR drop, and the device K operates, contacts 15 of the device K opening after a short time, so that the only way in which the relay CR can be restored and the brakes released is by operation of the reset device R. The reset device R can not be fastened down, because until it is restored, the device K can not be energized. Consequently, if the engineer fails to acknowledge the signal, not only are the brakes applied, but also the brakes can not be re-

leased until the apparatus is reset from the ground; whereas, as previously explained, if the engineer properly acknowledges the signal, he may release the brakes as soon as the 5 speed has been reduced to the predetermined control speed.

In the various modifications above described, no impulse is received at a clear signal, because at that time the coil 8 on the track 10 inductor is included in a closed circuit of low resistance, and serves to choke back or oppose the passage of flux through the core of said track element, thereby preventing a quick change in flux which acts under caution 15 conditions to operate the relay CR.

While different specific embodiments of the invention have been disclosed, it will be readily recognized that the invention is not limited to these precise forms, but is susceptible 20 of considerable modification and adaptation in practice. Also, it should be understood that in the interests of simplification various expedients that may be employed advantageously in practice to make a complete system 25 of train control have not been shown or described. I desire to have it understood, therefore, that the invention is not limited to the particular arrangements and construction of devices and circuits shown in the drawings.

30 What I claim is:—

1. In a train control system for railroads equipped with a block signal system, the combination with trackway means effective near the entrance to each block to communicate a 35 stopping influence if the corresponding signal indicates caution, of car-carried apparatus responding to said stopping influence and acting to apply the brakes of the car, said apparatus including means permitting release 40 of the brakes after the speed of the car has been reduced to a predetermined control speed provided the engineer has taken appropriate action just prior to and only just prior to the reception of said stopping influence.

45 2. In a train control system for railroads equipped with a block signal system, the combination with trackway means effective near the entrance to each block to communicate a stopping influence if the corresponding signal indicates caution, of car-carried apparatus, 50 comprising, brake applying means adapted whenever operated to continue in operation until restored, a manually operable reset device accessible only from the ground 55 for restoring said means, and other means rendered effective by a manual operation thereof by the engineer just prior to and only just prior to the initiation of operation of the brake applying means for restoring that 60 means after the speed of the car has been reduced to a predetermined low speed.

65 3. In a train control system for railroads equipped with a block signal system, the combination with trackway means effective near the entrance to each block to communi-

cate a stopping influence if the corresponding signal indicates caution, of car-carried apparatus comprising, a stick relay responding to said stopping influence, an electro-magnetic device having a circuit governed by 70 said relay; brake applying means controlled by the electro-magnetic device, manually operable means effective only if actuated prior to the operation of the brake applying means for restoring said stick relay, and means including a speed-responsive device driven from the wheels of the car for controlling the restoration of said electro-magnetic device. 75

4. In a train control system for railroads equipped with a block signal system, the combination with trackway means effective near the entrance to each block to communicate a stopping influence if the corresponding signal indicates caution, of car apparatus comprising, brake control means responding to said influence and operable to enforce reduction in speed of the car to a predetermined control speed, and manually operable means effective only if actuated just prior to and only just prior to the initiation of operation of the brake control means for permitting restoration of said brake control means after the predetermined control speed limit has been reached. 90

5. In a train control system, brake control apparatus including influence elements partly on the car and partly on the track, a stick device adapted to be deenergized by 95 said influence elements at each caution signal, and brake setting means eventually actuated by said stick device if said device continues to assume its deenergized position, said stick device when set into operation continuing in operation until restored, and means including an acknowledging device operable manually by the engineer and effective only if actuated prior to the initiation of operation of the brake setting means for restoring said stick device provided the speed of the car is below a predetermined low speed 100 and said acknowledging device is in its effective condition. 105

6. In a train control system, a brake setting appliance on the car which when once initiated continues in operation until restored, a stick relay on the car adapted when deenergized to initiate operation of said appliance, means partly on the car and partly on the track for temporarily deenergizing 115 said relay under dangerous traffic conditions, manually operable means effective only if actuated prior to the initiation of operation of the brake setting appliance for restoring said stick relay, and automatic means for 120 restoring the brake setting appliance to normal after the speed of the car has been reduced to a predetermined low speed and provided the stick relay has been restored. 125

7. A train control system for railroads 130

equipped with a block signal system, trackway means effecting the communication of a stopping influence to the car near the entrance to each caution block, a normally energized stick relay on the car deenergized by such stopping influence, brake setting means including an electro magnet having a stick circuit and controlled by said stick relay, means for restoring said magnet only if the relay is energized after the speed of the car has been reduced to a predetermined low speed, an acknowledging device effective only if actuated by the engineer prior to the operation of the brake setting means for re-energizing the stick relay, and manually operable means accessible only from the ground for independently reenergizing the stick relay.

8. In a train control system for railroads equipped with an automatic block signal system, the combination with traffic controlled trackway means, of brake control apparatus on a vehicle governed by said trackway means and having its operation initiated at each caution signal, and acknowledging device on the vehicle operable manually by the engineer and which if operated just prior to the passage of the vehicle by a caution signal prevents actuation of said brake control apparatus, said acknowledging device if left in its operated position for more than a predetermined time, actuating said brake control apparatus, means for restoring said apparatus after the vehicle has been brought to a stop which if left in its active position renders said brake control apparatus active, and other restoring means for said apparatus effective only if the speed of the car has been reduced to a predetermined low speed and the engineer has operated the acknowledging device prior to the operation of the brake control apparatus.

9. Car apparatus for train control systems comprising, brake setting means including an electro-pneumatic-valve, a stick relay controlling said valve, an acknowledging device manually operable by the engineer and effective only if actuated prior to the operation of said valve, and means for re-energizing the stick relay after the speed of the car has been reduced to a predetermined minimum provided said acknowledging device is then effective.

10. A system for automatically controlling the movement of railway trains comprising, brake setting apparatus on a vehicle automatically operated at each caution signal, a speed-responsive device driven from the wheels of the vehicle, contacts closed by the speed-responsive device if the speed is below a predetermined minimum, a circuit adapted when closed to cause restoration of said brake setting apparatus, said circuit including said contacts of the speed-responsive device, and manually operable means on the vehicle effec-

tive if actuated prior to operation of the brake setting apparatus to determine closure of said restoring circuit at another point, said manually operable means being so constructed that it cannot be permanently held in its active condition without effecting an automatic brake application.

11. Car apparatus for train control systems comprising, a brake setting appliance, a manually operable acknowledging device acting if maintained in its operated condition longer than a certain time to cause operation of said appliance, a circuit acting if energized to permit automatic restoration of said appliance, means preventing re-energization of said circuit until the speed of the car has been reduced to a predetermined low speed, means interrupting said circuit upon operation of said apparatus, and means for closing said circuit at one point upon operation of the acknowledging device.

12. A train control system characterized by the automatic initiation of the operation of brake control apparatus at each caution signal, and the provision of means permitting the release of the brakes provided the speed of the car is reduced to a predetermined minimum and provided a manual operation is made by the engineer prior to the initiation of the operation of the brake control apparatus, said last mentioned means including a manually operable acknowledging device which is normally in an inactive position and which is held in its active position for more than a predetermined period of time effects an automatic brake application.

13. Car-carried apparatus for automatic train control systems comprising, a permissive speed device normally in a maximum permissive speed condition which if initiated gradually restricts the speed of the train in accordance with the progress of the train, a normally energized stick device which if energized maintains said permissive speed device in its normal condition, means for deenergizing said stick device governed by control influences transmitted from the trackway, and manually operable means which if operated prior to the deenergization of said stick device closes a contact in said pick up circuit for said stick device at one point, and other means for closing said pick up circuit at another point.

14. In a system of train control of the character described, the combination of brake setting apparatus set into operation under dangerous traffic conditions and continuing in operation until restored, and means for determining restoration of said apparatus comprising, a speed-responsive device driven from the wheels of the car, and a manually operable acknowledging device effective only if actuated less than a predetermined period of time prior to and during the time of initiation of operation of said apparatus.

15. Car-carried apparatus for automatic train control system comprising, a stick relay having a stick circuit including a front contact of said relay, influence communicating means partly on the vehicle and partly along the trackway for deenergizing said stick relay under dangerous traffic conditions ahead, a stick electro-responsive device having a stick circuit including front contacts of said relay and said device, a normally energized brake setting device governed by said stick device which if deenergized applies the brakes of the train, manually operable means which if operated while said brake setting device is in its inactive conditions re-energizes said stick relay, and means for picking up said stick electro-responsive device effective if the speed of the train is below a predetermined value and said stick relay is in the energized position.
16. Car-carried apparatus for automatic train control systems comprising, a stick relay having a stick circuit including a front contact of said relay, influence communicating means partly on the vehicle and partly along the trackway for deenergizing said stick relay under dangerous traffic conditions ahead, a stick electro-responsive device having a stick circuit including front contacts of said relay and said device, a normally energized brake setting device governed by said stick device which if deenergized effects an application of the brakes, manually operable means which if operated while said brake setting device is in its inactive condition re-energizes said stick relay, means for closing a pick up circuit for said stick electro-responsive device effective if the speed of the train is less than a predetermined minimum and said stick relay is energized, and manually operable means only accessible from the ground for restoring said stick device to normal.

In testimony whereof I hereby affix my signature.

CHARLES S. BUSHNELL.
